UNITED STATES PATENT OFFICE.

GEORGE H. ULLMAN, OF NEW YORK, N. Y., ASSIGNOR TO L. PLAUT & COMPANY, OF NEW YORK, N. Y., A COPARTNERSHIP.

DESIGN FOR AN ELECTROLIER-BODY.

41,382.

Specification for Design.

Patented May 16, 1911.

Application filed February 28, 1911. Serial No. 611,536. Term of patent 7 years.

To all whom it may concern:

Be it known that I, GEORGE H. ULLMAN, a citizen of the United States, and a resident of the borough of Manhattan, city, county, and State of New York, have invented a new, original, and ornamental Design for an Electrolier-Body, of which the following is a specification, reference being had to the accompanying drawing, forming a part thereof.

In the drawing, Figure 1 is an elevation of an electrolier body showing my new design; and Fig. 2 is a plan view of half of the bottom thereof, the other half being exactly the same.

The design comprises a substantially cylindrical body having ornamented edges of beaded and ribbed form; the curved portion having represented thereon in relief a plu-

rality of grotesque, bearded, human heads, between which are festoons of leaves and grapes, ribbons being looped above the heads and having their ends extending down at each side thereof; and the bottom being convex at the middle portion and having represented thereon a rosette surrounded by conventional forms of foliage and blossoms.

I claim:

The ornamental design for an electrolier body, as shown and described.

Signed at New York city, county of New York, and State of New York, this 24 day of Feby., 1911.

GEORGE H. ULLMAN.

Witnesses:

JOHN L. LOTSCH,
GUSTAV A. SCHELLACK.
